Specification of Letters Patent. Patented Oct. 24, 1916.

Application filed August 24, 1911. Serial No. 645,794.

To all whom it may concern:

Be it known that I, PRESTON UPHAM, a citizen of the United States, residing at Boston, Suffolk county, State of Massachusetts, have invented an Improvement in Presses, of which the following description, in connection with the accompanying drawings, is a specification, like characters on the drawings representing like parts.

10 My invention, one embodiment of which is illustrated in the accompanying drawings and herein described, relates to certain improvements in presses which improvements possess many features of novelty and invention which are useful either in combination with each other as disclosed, or as used separately in any type of press. One of these features is my pressure creating and pressure transmission system. Another is my 15 improved construction for operating and timing my mold opening, filling, and closing means. Many other features of novelty will be explained hereinafter.

20 The drawing shows a diagrammatic view of the press.

25 In the embodiment of my invention disclosed in this drawing the driving pulley 1, driven by a belt from any suitable source of power such as a motor, is shown keyed on the shaft 2, to which is keyed the pinion 3. The pinion 3 meshes with the gear 4 keyed on the timing shaft 5. The timing and pressure actuating shaft 5 is provided with a crank 6. A connecting rod 7 connects said 30 crank with a displacing plunger 8 which reciprocates in a part of a chamber 9 of the hydraulic cylinder 10. In lieu of the crank 6, I may, without departing from the spirit of my invention, use any other suitable pressure actuator preferably one having a fixed 35 throw, as, for example, an eccentric or cam, altering the connection with the plunger 8 to correspond. The hydraulic cylinder 10 is provided with pressure responsive means 40 herein shown as a ram 11 although a diaphragm may be used without departing from the spirit of my invention.

45 The receptacle or chamber between the displacing plunger 8 and the ram 11 is filled 50 with a normally substantially constant body or fixed quantity of liquid which serves to transmit pressure imparted by the displac-

ing plunger to the ram, and also, by reason of the larger surface of the ram serves to increase or multiply the pressure so transmitted. It will be seen that revolution of the timing shaft 5 will produce reciprocation of the ram 11 and that the pressure applied to the displacing plunger 8 will be multiplied when transmitted to the ram 11. 55 in the same ratio as the respective areas of the displacing plunger and ram. In order that excessive resistance to compressive movement of the ram may not stall the timing shaft or break any of the parts, and also 60 to provide a dwell or period of high compression, I have provided automatic pressure determining, or controlling means, which, in the embodiment herein disclosed, comprises a sliding bed 12 reciprocable on 65 the bed of the press, on which sliding bed is mounted the actuating motor, the shaft 2, the shaft 5 and hence the crank 6. Co-operating with this sliding bed is a steam cylinder 13 provided with a piston 14 and 70 a piston rod 15 connected to the sliding bed 12 in such a manner that fluid pressure in one end of the cylinder 13 will tend to keep the bed 12 in its position nearest the hydraulic cylinder 10 except when a predetermined resistance to inward motion of the displacing plunger has been reached. This, 75 as may be readily seen, will be reached only when a predetermined resistance is opposed to compressing movement of the ram 11. 80 When this occurs, the displacing plunger 8 will stop its inward stroke and the sliding bed 12 will be forced back by further rotation of the shaft 5 against the pressure of 85 the fluid in the fluid pressure cylinder 13. 90

The before described mechanism constitutes one form of compensating means to compensate or provide for a longer or shorter stroke of the displacing plunger against the liquid in case of varying amounts 95 of material in the mold and consequently varying resistances to the movement of the displacing plunger.

It will be noted that in the embodiment herein described the actuator and its accessories are made movable bodily with the sliding bed but it is evident that these parts might be fixed and the remainder of the press made movable on a sliding bed with-

out departing from the spirit of my invention.

The cylinder 10, the displacing plunger 8 and the fluid pressure cylinder 13 and the amount of liquid in the chamber 9 are all so proportioned that the pressure at which the bed begins to move away from the cylinder 10 may be normally reached before the displacing plunger 8 reaches the end of its stroke.

The pressure system one form of which is herein disclosed is designed primarily to operate with an automatically operating mold, for the compression of blocks, bricks, tiles and the like, made from asphaltic or other plastic material. I have shown in the drawings a mold containing member 17 having a mold 18 and connected to the hydraulic cylinder 10 by bolts 18^a, and a plunger 19 operable by the ram 11 through the member 19^a. To fill this mold 18, to cover it when the material therein is being pressed and to uncover it when said mold is being emptied, it is necessary to provide operating means to change the relative position of the mold and mold cover.

In the embodiment herein described in which a sliding mold cover is used, I have shown a sliding head 20 containing the filling neck 21 and the mold cover or pressure receiving block 22. In the embodiment shown, it is necessary that the sliding head 20 should be automatically movable into three positions respectively, for filling as shown in the drawing, for pressing with the pressure receiving block 22 covering the mold and for ejection with the head removed from over the mold entirely. In the embodiment herein described, I accomplish this by the use of two fluid pressure cylinders. Of these one shown at 24 contains the piston 25 operating the piston 26, the piston 25 having a stroke limiting means herein shown as the tail rod 27, the link 28 and the fixed pin 29 attached to any suitable and convenient support. I may use a crank or any other suitable stroke limiting device without departing from the spirit of my invention. In the embodiment of my invention shown, the piston rod 26 is not attached to the sliding head but abuts against it. Another fluid pressure cylinder 30 is provided with a piston 31, a piston rod 32 connected to the head, and the tail rod 33 provided with stroke limiting means herein shown as the link 34 and the fixed pin 35 attached to any suitable support.

The operation of the head moving means may be timed as follows: On the timing shaft 5 which as shown in that embodiment of my invention illustrated in the drawings also operates as the crank shaft of the press are mounted any suitable cams or other well known mechanical device or means. Of these one, through any suitable connection,

a part of which is shown at 38 and one embodiment of which will hereafter be explained more fully, operates the slide valve 39 in the valve chest 40 which controls the inlet and outlet of steam or fluid pressure from the cylinder 24. Fluid pressure is preferably admitted to one end of this cylinder only. Any suitable inlet may admit steam to the valve chest 40, and any suitable exhaust port 41 may serve to exhaust steam from the cylinder 24. Another cam or the like on the shaft 5, through any suitable connection, a part of which is shown at 43, operates the slide valve 44 in the steam valve chest 45. This slide valve 44 controls the admission and exhaust of steam from the opposite ends of the cylinder 30. The exhaust pipe 46 is preferably provided with a safety valve 47 so that when one end of the cylinder is exhausting, a relatively low pressure will still be maintained therein. This serves to maintain a low pressure in the end 60 of the cylinder 30 when the steam pressure in the cylinder 24 is moving the sliding head into pressing position and prevents any momentum acting to continue movement of said sliding head after the piston 25 has completed its stroke.

After the compression of the block in the mold and the uncovering of the mold, I provide ejection or mold emptying means preferably operated by fluid pressure. In the embodiment of my invention herein disclosed, I accomplish this by a fluid pressure operated ejecting cylinder 48 having a piston 48^a and the piston rod 48^b operating through the connecting rod 49 on the bell crank 50 pivoted on the shaft 51 which operates to lift the member 19^a and the plunger 19 to eject the block. The point to which the plunger is to be raised by this fluid pressure cylinder is determined by any suitable stroke limiting device herein shown as lugs having set screws 52, which may be adjusted to allow the plunger to be elevated to such a height only as to be flush with the top of the mold containing member 17. Steam is admitted and exhausted from the ejecting cylinder 48 by means of a slide valve 53 located in any suitable valve chest 54. The slide valve 53 is preferably operated by a cam on the timing shaft 5. In order that the operation of this cam on the timing shaft 5 may not be affected by the change of position of the timing shaft which takes place when a predetermined pressure on the contents of the mold has been reached, I have herein provided a bar 53^a positioned above this cam and mounted on guides in such a manner that it will always remain parallel to the plane in which the sliding bed 12 is movable. Springs 53^c are provided to keep the bar in its position nearest the timing shaft except when it is elevated by the cam act-

ing on its lower surface. When the cam moves this bar the latter remains parallel to the plane in which the sliding bed moves and transmits movement through the connection 53^a to the slide valve 53. The connections to the slide valves 44 and 39 are preferably of similar design.

The operation of the press is as follows: In the position shown in the drawing, the 10 mold has just been filled. Fluid pressure is now admitted to the end 57 of the fluid pressure cylinder 24 by movement of the slide valve 39. The pressure in the cylinder 30 being low, mold member 17 is pushed by 15 the rod 26 until the pin 29 stops the link 28. As explained before, if desired, a relatively low pressure may be maintained in the cylinder 30 to prevent the momentum of the mold member from carrying it past the 20 desired pressing position. The crank 6 which revolves clockwise now starts the displacing plunger 8 on its inward travel starting the ram 11 on its upward travel. This continues until a predetermined pressure is reached 25 on the contents of the mold, the pressure determining or controlling piston 14 then responds by receding in its cylinder 13 thus permitting the sliding bed 12 carrying the pressure actuator to recede thus stopping 30 the displacing plunger 8 on its inward stroke yet permitting the crank 6 to complete its stroke.

It is manifest, in the embodiment of my invention herein shown, that normally from 35 the instant that the resistance to the displacing plunger causes movement of the pressure determining or controlling piston until that piston resumes its starting position, after the crank 6 has made the necessary part of its return stroke, a substantially uniform predetermined pressure will be maintained upon the contents of the mold through the compressing plunger and ram. This pressure will be thus applied for a period 45 which is believed to be approximately twice the length of time that a uniform pressure can be maintained upon any positively actuated hydraulic press of like capacity of the safety valve, liquid expulsion type. This increased dwell or period during which 50 a high compression is maintained is valuable to effect a more perfect compression of the material in the mold.

The pressing operation being completed 55 when the displacing plunger has receded sufficiently to relieve all pressure from the material in the mold, it is necessary to uncover the mold so that the compressed material may be ejected therefrom. To perform 60 this, steam is admitted to the end 58 of the cylinder 30 by moving its slide valve 44 into proper position. This causes the head to be moved to its position at the extreme right as allowed by the link 34 and 65 the pin 35. The mold is now uncovered.

The slide valve 53 is now moved to a position such that fluid pressure is admitted to the end 59 of the cylinder 48. This, through the connections before explained, causes the block to be ejected from the mold. Fluid 70 pressure is now admitted by slide valve 44 to the end 60 of the cylinder 30. This causes the sliding head to move to the extreme left position allowed by the link 34 and pin 35 in which position the neck 21 75 registers with the mold 18, the fluid pressure in the cylinder 24 having first been exhausted by the action of the slide valve 39. The fluid pressure is now exhausted from the end 59 of the cylinder 48 and if necessary, other fluid pressure may be admitted to the opposite end of the cylinder 48 to assist in allowing the plunger 19 and the member 19^a to fall and cause the mold to be again filled with unpressed material 80 from the neck 21. Any suitable device as shown at 61 may be used to vary the downward stroke of the plunger and hence the amount of material admitted to the mold and the thickness of the resultant block. 90

As will be readily seen by the construction shown in the present embodiment of my invention, the pressure creating means is actuated independently of my mold operating means. By this arrangement, in case of 95 any obstruction to the sliding head moving or block ejecting means, the pressing power which is very great is not effective to break any of the parts, yet they are all relatively timed together. My hydraulic transmission 100 system obviates the necessity for constantly supplying new liquid as is the case with the usual types of mechanically actuated hydraulic presses which are supplied with safety valves to permit escape of the liquid 105 when a predetermined pressure is reached. By my system, the main pressure ram is synchronously responsive to every movement of the displacing plunger which though mechanically actuated may have a variable 110 travel determined by the resistance opposed thereto. The construction shown, as before explained, also prolongs the dwell during which the material is subjected to its maximum pressure, because the maximum pressure is continued during the stroke of pressure controlling plunger in both directions, normally continuing during a part of the stroke of the crank actuator in both directions. I preferably provide a replenishing 115 pump 62 adapted to replace any liquid which may leak or escape from the chamber 9.

While I have shown an improvement in pressure-imparting mechanisms, such improvement is not claimed in this application but is claimed in my copending, divisional application Serial No. 114,710, filed 125 August 14, 1916.

Having thus described one embodiment of my invention, I wish it understood that 130

my invention is not limited to the constructions and combinations herein shown and described but

What I desire to claim broadly by Letters Patent is set forth in the following claims:—

- 5 1. A press comprising in combination a mold; a mold cover and automatically timed fluid pressure means to impart to and fro movement to change the relative position 10 of said mold and mold cover into three or more relative positions.
- 15 2. A press comprising in combination a mold; a mold cover; a mold plunger; compressing means; a plurality of fluid actuated pistons with piston containing means there- 20 for to transversely change the relative position of said mold and mold cover into three or more relative positions, and automatic timing means to time such relative change of position.
- 25 3. A press comprising in combination a mold; a mold cover; a plurality of fluid actuated pistons operating in cylinders to change the relative position of said mold and mold cover; a safety valve for the ex- 30 haust of one of said cylinders to maintain a low pressure in said cylinder when said cylinder is open to said exhaust, whereby said low pressure may prevent undesired relative movement of said mold and mold cover.
- 35 4. A press comprising in combination a mold; a mold cover; operating means comprising fluid pressure means to change the relative position of said mold and said mold cover into three or more relative positions; a positive mechanical prime mover for said press; common timing means to time the operation of said operating means and said 40 prime mover, and independent actuators

for said operating means and said prime mover.

5. A press comprising in combination a mold; a mold cover; operating means comprising fluid pressure means to change the 45 relative position of said mold and said mold cover; fluid pressure emptying means; a positive mechanical prime mover for said press; common timing means to time the operation of said operating means, said 50 mold emptying means and said prime mover, and independent power actuators for said operating means, said mold emptying means and said prime mover.

6. A press comprising in combination a 55 mold; a mold cover; operating means to move relatively said mold and said mold cover into a plurality of positions, said operating means comprising a fluid pressure cylinder and stroke limiting means exterior 60 to said cylinder to determine the relative positions of rest of said mold and mold cover by limiting the stroke of the piston in said cylinder.

7. A press comprising in combination a 65 mold; a mold cover; operating means to move relatively said mold and said mold cover into a plurality of positions, said operating means comprising a fluid pressure cylinder and stroke limiting means to de- 70 termine the relative positions of rest of said mold and mold cover by limiting the stroke of the piston in said cylinder.

In testimony whereof I have signed my name to this specification in the presence of 75 two subscribing witnesses.

PRESTON UPHAM.
